DOUBLE ACTION SAFETY SWITCH

John Herman Bretthauer and William Cermak,
New York, N. Y.

Application December 6, 1940, Serial No. 368,960

5 Claims. (Cl. 290—107)

This invention relates to safety switches used in circuits wherein a battery is being charged by a generator.

The main object of this invention is to provide a double-action safety switch which will protect all the electrical equipment in such circuits.

Another object of this invention is to provide a double-action safety switch having an angularly shaped armature and to mount the said armature at one end thereof while the other end contacts blocks forming the terminations of contact carrying arms so as to cause an increase in the pressure between the contact points when the armature is being pulled down due to an excess voltage in the generator above normal.

Another object of this invention is to provide a combined circuit-opening and circuit-closing induction type switch having two electromagnets, one of which is adapted to draw down the armature when there is an excess voltage produced in the generator due to a loose or open connection in the battery circuit, and the other electromagnet is adapted to draw down the armature when there is a short circuit in the lighting circuit, such as that used in automobiles.

Another object of this invention is to provide a combined switch having two independently acting electromagnets and two sets of successively breaking contact points, one set for the lighting circuit and the other set for the generator field circuit, and to so arrange the breaking of the contact points that the contact points for the lighting circuit will break before breaking the contacts for the generator field circuit.

With the above and other objects in view, the invention will be hereinafter more particularly described, and the combination and arrangement of parts will be shown in the accompanying drawings and pointed out in the claims which form part of this specification.

Reference will now be had to the drawings, wherein like numerals of reference designate corresponding parts throughout the several views, in which:

Figure 1 is a plan view of a switch embodying the invention.

Figure 2 is a front elevational view of the switch shown in Figure 1, without the fuses and electric lamp shown in Figure 1.

Figure 3 is a fragmentary section on line of 3—3, Figure 1.

Figure 4 is a diagrammatic representation of the elements of the invention and their electrical connection as applied to circuits wherein

lights are shown in conjunction with a battery and generator.

Figure 5 is a fragmentary view of the switch, partly broken away, to show a control device for raising or lowering the armature.

In the illustrated embodiment of the invention, the numeral 10 indicates a double-action safety induction type switch comprising an armature 11 which has been hinged at 12, to one end of an angularly shaped bracket 13 fixed to the upper surface of an insulating base-plate 14 by screws 15.

The bracket 13 has been positioned to provide an upright extension 16 forming a magnetic leg with which the armature tends to complete the magnetic circuit when electromagnets are energized.

The armature 11 has an aperture 17 permitting passage therethrough of a hook 18 which is integral with the extension 16 and acts as a stop and limits the upward movement of the armature 11. An electromagnet 19 serving as a voltage control, has an iron core 20, the lower end of which has been fixed to the horizontal leg of 25 the bracket 13.

The iron core 20 has been wound with insulated copper wire having a number of turns to magnetize the core and be adapted to pull down the armature against the resistance of springs 30 and blocks which normally maintain the armature in contact with the stop 18 and away from contact with the extension 16. Under operating conditions, when the armature 11 contacts the extension 16, there is a clearance between the lower surface of the armature and the top of the iron core 20.

A pull spring 21 has been secured to the base-plate 14 by a screw 23. A screw 22 has been threaded in insulating material 23 secured by screws 24 to the upper surface of the armature 11. The screw 22 passes through an oval shaped clearance hole (not shown) in the pull spring 21 and serves as a means for adjusting the tension of the spring 21 and causing a constantly acting pull on the armature. The spring 21 pulls the armature away from the upper surface of the extension 16, and tends to bring the armature up to the upper stop 18.

As best shown in Figure 2, a contact 25 has been fixed to the pull spring 21. A contact 26 is carried by a spring arm 27. The spring 27 has been secured to the base-plate 14 by a screw 29. Normally, the contacts 25 and 26 are in separated relation and control an auxiliary circuit,

and the armature 11 is in spaced relation from the extension 16.

A spring arm 30 carrying a contact 31 has been fixed to the base-plate 14 by a screw 33. A spring arm 34 carrying a contact 32 has been fixed to the base-plate 14 by a screw 35. Normally, the contacts 31 and 32 are in contacting relation, and control a primary circuit.

As shown in Figure 3, a spring arm 40 carrying a contact 41 has been fixed to the base-plate 14 by a screw 43. A spring arm 44 carrying a contact 42 has been fixed to the base-plate 14 by a screw 45. It is to be noted that the contacts 41 and 42 are positioned rearwardly of the contacts 31 and 32. Normally, the contacts 41 and 42 are also in contacting relation, and control a primary circuit.

The upper portions of the spring arms 30 and 40 extend above the armature a sufficient distance to permit attaching thereto of insulating or non-conducting blocks 46 and 47. Normally, the free end 48 of the armature 11 is held in frictionally contacting relation against the blocks 46 and 47. The blocks 46 and 47 are held in position by screws 49 and 50 in the spring arms 30 and 40. As best shown in Figure 2, the bottom surfaces of the blocks 46 and 47 are in substantially horizontal planes.

It is to be noted that the bottom surface of the block 47 is above the bottom surface of the block 46. This arrangement of the blocks 46 and 47 is for the purpose of releasing block 47 before releasing block 46 and in order to break the contacts 41 and 42 before breaking the contacts 31 and 32. Under operating conditions the contact points 41 and 42 are in series with the lighting circuit, while the contact points 31 and 32 are in series with the generator field circuit. The prior breaking of the contact points 41 and 42 protects the electric lights from burning out, as is the case when there is a loose or broken connection in the battery circuit.

As shown in Figure 2, it will be seen that the armature 11 is normally angularly positioned above the horizontal plane, that is, the upper leg of the armature makes an obtuse angle with the upright leg. This angular position of the upper leg of the armature functions so that when the said armature is pulled down by the electromagnet 19 against the upper surface of the angular extension 16, there is a forward movement against the blocks 46 and 47. This forward movement increases the pressure on the contact points to take care of the overload on the points 31 and 32, and 41 and 42, which would be due to a loose connection in the battery circuit. It is to be noted that in case of an open circuit in the battery line, the sudden increase in generator voltage above normal will also cause the electromagnet 19 to rapidly pull down the armature and function to protect electric lights and other electrical equipment in the circuits.

An electromagnet 59 serving as a short circuit control has an iron core 60, the lower end of which has been fixed to the horizontal leg of the bracket 13. The iron core 60 has been wound with insulated copper wire of heavier gauge than the wire on the electromagnet 19. The winding on the core 60 serves to magnetize the said core so as to be also adapted to pull down the armature against the resistance of the spring 21 and the blocks 46 and 47. It is to be noted that during the time the electromagnet 59 pulls down the armature 11, there will be the same increase in pressure on the contact points 31 and 32, and

41 and 42. As best shown in Figure 2, the electromagnets 19 and 59 are mounted on the bracket 13 in spaced-apart relation.

Operation of invention

As shown in Figure 4, the double action safety switch 10 is in circuit with and serves to protect electric lights 65 and an auxiliary battery 63. An indicator light 70 in circuit with the auxiliary battery 63 serves to visually signal to the operator that there is a loose or broken connection in the circuit of the storage battery 64, or that fuse 72 has been burnt out due to a short circuit in one of the primary circuits.

For the purpose of the invention there has been provided auxiliary or emergency lights 63 and an auxiliary battery 63. An indicator light 70 in circuit with the auxiliary battery 63 serves to visually signal to the operator that there is a loose or broken connection in the circuit of the storage battery 64, or that fuse 72 has been burnt out due to a short circuit in one of the primary circuits.

An indicator light 71 in parallel shunt with the short circuit electromagnet 59 serves to visually signal to the operator that there is a short circuit. The indicator light 71 lights only when fuse 73 burns out. The fuse 73 is destroyed by excessive temperature caused by abnormal electrical conditions such as excessive current flow. Current from the battery is now automatically diverted to the electromagnet 59 which becomes fully energized and powerful enough to pull down the armature 11. The fuse 72 serves to protect the electric lights 65 while fuse 73 serves to protect the ammeter 74, and the generator 67, and other circuits connected thereto in the event of a short circuit or in the event that the generator cutout 70 fails to break the circuit.

The circuits shown may comprise an ignition fuse 75, 76, a heater fuse 77, and a horn fuse 78.

In the event that any one of these fuses 75 to 78 inclusive burn out, the circuit of the switch 10 may not be effected because these fuses have a smaller carrying capacity than the fuse numbered 73.

Regardless of which electromagnet 19 or 59 causes the armature to be drawn to the extension 16 of the bracket 13, the contacts 41 and 42 break prior to the breaking of the contacts 31 and 32. This arrangement serves to first break the light circuit before breaking the field circuit.

It is to be noted that the friction pressure blocks 46 and 47 provide a predetermined tension against downward movement of the armature. When the armature has been drawn down by one of the electromagnets, the block 46 holds the armature down so as to cause contacts 31 and 32, and 41 and 42 to stay open, and to keep contacts 25 and 26 closed.

The screw 22 may be adjusted so as to increase or decrease the pull of the spring 21 on the armature from the extension 16 so as to insure the maintenance of the armature against the upper stop 18 under normal conditions. In the event of an increase of voltage in the generator above normal, the pull from the electromagnet 19 will overcome the tension of the spring 21 and pull the armature down to trip the blocks 46 and 47.

It is to be noted that the electromagnet 19 is connected in circuit with the generator 67 and will operate only when the generator is in operation. When the armature trips the blocks 46 and 47, the upper surface of the armature comes below the lower surface of the block 46. The block 46 then holds the armature down. Due to the movement of the block 46 over the arma-

ture, the field circuit of the generator is broken and the electromagnet 19 is demagnetized.

When both indicator lights 78 and 71 are burning, it indicates that fuse 73 is burnt out. If light 78 only burns it indicates a loose connection or open circuit or a burnt out fuse 72.

For the purpose of raising the armature 11 to the normal operating position shown in Figures 2 and 5 after the armature was pulled down, we have provided a lever 80 made of flat spring metal fulcrumed at 81 and having a cam-shaped member 82 which is normally out of contact with the blocks and with the armature 11.

When it is desired to raise the armature after being pulled down, the operator moves the lever 80 towards the blocks 45 and 47, and the cam-shaped member 82 moves the blocks to the right and permits the spring 21 to raise the armature up to normal operating position.

When it is desired to close the circuit to the auxiliary lights, the operator can move the lever 80 to the left and cause the cam-shaped member 82 to press down the armature and release the blocks to permit said blocks to move above the upper surface of the armature and to hold the armature down.

It is to be noted that due to the manner of hinging the armature 11 at its lower end 12 that there are both horizontal and vertical movements at the free end of the armature. These combined movements facilitate the downward motion of the armature to the electromagnets.

It is also to be noted that when there is a leak in a storage battery cell or the electrolyte becomes low, the resistance in the battery circuit would increase and allow the generator voltage to rise, thereby increasing the energy of the electromagnet 19 and causing the armature 11 to be attracted toward the electromagnet and break the light and field circuits and close the auxiliary light circuit.

In the application of our invention to the protection of electrical equipment including auxiliary and main light circuits, we may provide a single two-circuit combination switch (not shown) to control both light circuits simultaneously.

It will thus be seen that this invention is adapted to protect all the electrical appliances that are generally used in circuits wherein a battery is being charged by a generator, and appliances in electrical circuits in general.

In accordance with the patent statutes we have described and illustrated the preferred embodiment of our invention, but it will be understood that various changes and modifications can be made therein without departing from the spirit of the invention as defined by the appended claims.

It will thus be seen that there has been provided an electro-magnetic safety switch wherein a plurality of primary circuits having contacts 31-32, and 41-42, which are normally closed, are successively opened. Also, that a normally open auxiliary circuit having contacts 25-26 is closed after one set of primary circuit contacts are broken.

We claim:

1. A device of the character described comprising in combination a magnet coil, an L-shaped armature lever having one end pivoted adjacent the base of said coil whereby its free end has a movement in response to said coil having both a horizontal and a vertical component and being spring-pressed away from said

coil, a pair of switches mounted adjacent to said free end each having a movable member carrying a block, said member being spring-pressed toward said armature end and in a direction to open said switch, each block having a horizontal and a vertical face of such dimensions that when the vertical faces are engaged by said free end, both switches are held closed and when said free end comes beneath the horizontal faces both switches are released to open and said lever is held by one of said faces in magnet operated position, one of said horizontal faces being higher than the other, whereby one switch is opened before the other.

2. A device of the character described comprising in combination a magnet coil, an L-shaped armature lever having one end pivoted adjacent the base of said coil whereby its free end has a movement in response to said coil having both a horizontal and a vertical component and being spring-pressed away from said coil, a pair of switches mounted adjacent to said free end each having a movable member carrying a block, said member being spring-pressed toward said armature and in a direction to open said switch, each block having a horizontal and a vertical face of such dimensions that when the vertical faces are engaged by said free end, both switches are held closed and when said free end comes beneath the horizontal faces both switches are released to open and said lever is held by one of said faces in magnet operated position, and a manual releasing member movable to engage said switch members to cause said blocks to disengage said horizontal faces from said armature lever and having a member for engaging said lever to depress the same on movement of said releasing member in the other direction, to release said switch members.

3. A device of the character described comprising in combination a magnet coil, an L-shaped armature lever having one end pivoted adjacent the base of said coil whereby its free end has a movement in response to said coil having both a horizontal and a vertical component and being spring-pressed away from said coil, a pair of switches mounted adjacent to said free end each having a movable member carrying a block, said member being spring-pressed toward said armature end in a direction to open said switch, each block having a horizontal and a vertical face of such dimensions that when the vertical faces are engaged by said free end, both switches are held closed and when said free end comes beneath the horizontal faces both switches are released to open and said lever is held by one of said faces in magnet operated position, the armature and switch members being so constructed and arranged that as said armature is moved toward its operated position, it increases the pressure on said vertical faces to increase the pressure of contact of said springs, until it passes beneath said horizontal faces.

4. A device of the character described comprising in combination, a magnet coil, an armature lever pivoted adjacent said coil and spring pressed away from said coil, a pair of switches mounted adjacent the free end of the armature each having a movable member carrying a block, said member being spring pressed toward said armature end and in a direction to open the switch, each block having a face inclined to the direction of movement of the end of the armature whereby the movement of the armature may

close said switch and a horizontal face, the dimensions of said block being such that when the armature passes below the horizontal faces it is held down, one of said horizontal faces being higher than the other whereby as said armature is actuated one of said switches will open before the other.

5. A device of the character described comprising in combination, a magnet coil, an armature lever pivoted adjacent said coil and spring pressed away from said coil, a pair of switches mounted adjacent the free end of the armature each having a movable member carrying a block, said member being spring pressed toward said armature end and in a direction to open the 15

switch, each block having a face inclined to the direction of movement of the end of the armature whereby the movement of the armature may close said switch and a horizontal face, the 5 dimensions of said block being such that when the armature passes below the horizontal faces it is held down, and a manual releasing member movable to engage said switch members to cause 10 said blocks to disengage said horizontal faces and having a member for engaging said lever to depress the same on movement of said releasing member in the other direction.
